SET OF EDUCATIONAL TILES

Micah Jenkins, Ridgefield, Conn.

Application May 21, 1957, Serial No. 46,260

Term of patent 14 years

(Cl. D25—1)

FIG. 1.

FIG. 2.

I claim:

The ornamental design for a set of educational tiles, as shown.
